UNITED STATES PATENT OFFICE.

RICHARD SANFORD, OF PROVIDENCE, RHODE ISLAND.

TROUSERS-JACK.

SPECIFICATION forming part of Letters Patent No. 358,128, dated February 22, 1887.

Application filed May 5, 1886. Serial No. 201,254. (No model.)

To all whom it may concern:

Be it known that I, RICHARD SANFORD, a citizen of the United States, residing at Providence, in the county of Providence and State 5 of Rhode Island, have invented certain new and useful Improvements in Pantaloons-Jacks; and I do declare the following to be a full, clear, and exact description of the invention, such as will enable others skilled in the art to which 10 it appertains to make and use the same, reference being had to the accompanying drawings, and to the letters and figures of reference marked thereon, which form a part of this specification.

15 This invention relates to an improved trousers-jack designed to assist in the drawing off a pair of trousers from the legs of the wearer; and it consists, essentially, of a base or frame provided with two jaws, one of which is formed 20 integral with said base or frame, the other being pivoted thereto and provided with a foot-piece, by which the jaws are opened, said jaws being closed by means of a spring located between the foot-piece and the base or 25 frame, the two jaws being shaped properly to receive a trousers-leg and grip and retain the same while the leg of the wearer is being withdrawn therefrom, all substantially as will be hereinafter more fully described.

30 Figure 1 represents a side view, in partial section, of my improved trousers-jack. Fig. 2 is a plan view of the same.

Referring to the drawings, A represents my improved trousers-jack, consisting of the base 35 a, provided with the jaw b, formed integral with the base, the upper portion of said jaw being concavo-convex in form, with the convexity toward the center of the base. The upper portion of the base a, below the jaw b, 40 is provided with a supplemental jaw, c, pivoted at a', and provided with a foot-piece, d, extending over the base a, by means of which the jaw c is opened, said jaw being closed and furnished with a strong grip by means of the 45 spring e, located between said foot-piece and the base, being retained in position by the lug e' on the foot-piece and the barrel projection b' on the base, as fully shown in Fig. 1. The upper portion of the jaw c is also concavo- 50 convex in form, with the concavity toward the jaw b, the inner surfaces of the two jaws corresponding to each other, the jaw c extending

above the top of the jaw b to form a guide for the trousers-leg in operating the device, as fully shown in Fig. 1.

55

The inner face of either of the jaws may be provided with a surface of rubber, c', or other pliable substance, to enable the jaws to retain a firm grip of the trousers, as well as to protect the cloth from injury by contact with the 60 metal jaws of the device.

The base is provided with suitable screw-holes, b', whereby the device may be secured to the floor or to a suitable block.

In Fig. 1 of the drawings, d' represents, in 65 dotted lines, the lower back portion of a trousers-leg, and a' the toe of a boot as operating the device. The jaw c being opened, as indicated in dotted lines in Fig. 1, by a pressure of the foot on the foot-piece d, the trousers-leg is inserted 70 between the open jaws, as indicated in dotted lines d' in the same figure. The pressure of the foot is then removed and the spring e closes the jaw c, causing said jaw to firmly grip the trousers-leg. The leg of the wearer is then 75 withdrawn therefrom, the trousers-leg is then released from the jaws, and the same operation repeated with the remaining trousers-leg.

I have described the device as shown in the 80 drawings. It is evident that the general construction and arrangement of the parts with relation to each other may be varied considerably without departing from the spirit of my invention. The number of gripping-jaws 85 may be increased, also the foot-pieces, the object being to form gripping-jaws to be operated by the foot in such a position that a trousers-legs may be retained therein while the legs of the wearer are being withdrawn therefrom.

I am thus enabled to provide a device which 90 will be especially appreciated by corpulent men, whose obesity renders the drawing off of their trousers difficult. The device is simple in construction and easily operated, and is admirably adapted for the purpose contemplated. 95

Having described my invention, I claim—

1. A trousers-jack consisting of a base portion provided with corresponding concavo-convex gripping-jaws, said jaws being provided on one of their inner adjacent surfaces 100 with a covering of rubber or other pliable substance, one of said jaws being pivoted to the other and provided with a foot-piece for operating said jaw, and a spring for closing the

same located between the base and the foot-piece, arranged for use substantially as described.

2. A trousers-jack comprising a base and two corresponding concavo-convex gripping-jaws, one of said jaws being pivoted and provided with a foot-piece and a spring for operating said jaw, whereby a trousers - leg is gripped and retained between said jaws while

the leg of the wearer is being withdrawn therefrom, as set forth.

In testimony whereof I affix my signature in the presence of two witnesses.

RICHARD SANFORD.
